UNITED STATES PATENT OFFICE

ALBERT C. FISCHER, OF CHICAGO, ILLINOIS, ASSIGNOR TO THE PHILIP CAREY
MANUFACTURING COMPANY, A CORPORATION OF OHIO

ROOFING MEMBER WITH MARGINAL RIDGES

Application filed July 17, 1920, Serial No. 396,992. Renewed April 30, 1937.

The present invention relates to roofing materials produced in the form of roofing members which, for the sake of economizing in material, make special provision for weather-proofing along the lines of their overlap, so that the extent of lapping can be greatly reduced and a great saving in material can be effected. While not limited in its application, the invention is particularly appropriate to roofing materials of fibrous composition, metal or other sheet form.

One feature of the invention consists in forming along the marginal portions of the roofing members, ribs, ridges, flanges, or the like, of which those occupying the portion of the roofing member which is covered up in the assembly of the roofing member project upwardly, while those carried by the weathering or exposed portion of the roofing member extend downwardly so that the elements will be prevented from passing the overlapped members even though the extent of overlapping be reduced merely to the combined thickness of the interlocking ribs or the like.

Another feature of the invention consists in utilizing the lapped portions of the roofing members in one row as the trough or weathering surface of the space between the weathering members of the next succeeding row, so that the overlapping portion of each member in one row, with its down-turned ridges, bridges the space between the trough-forming portions of the members of the next lower row; and a feature collateral to this part of the invention consists in making each member with a relatively wide and a relatively narrow portion, with the corresponding portions of the several members symmetrical, and with the wide portions of the members complementary to the narrow portions, so that blanks for the roofing members can be cut from a continuous strip of material without substantial waste.

Further features of the invention relate to details through which the above-mentioned general features and various modifications thereof may be realized.

In the accompanying drawing—

Figure 1 represents one form of roofing

member embodying the subject-matter of the present invention; Figure 1a shows the method of assembling a plurality of such members; and Figures 2 and 3 are, respectively, the blank from which it is made, and 55 a strip of material from which such blank may be cut without waste.

Figure 4 is a modification of the member shown in Figure 1, according to which several members are formed integrally with a 60 connecting strip.

Figure 5 represents a method of cutting from a continuous strip the form of roofing member shown in Figure 4.

Figures 6 and 7 represent two complementary roofing elements cut from a single piece, and each embodying a series of tabs or design producing portions projecting integral- 65 ly from a continuous carrying strip of such width that the continuous portion of each 70 roofing member will provide an underlay for the tabs of the next succeeding member.

Figure 8 shows a method of assembling the members shown in Figures 6 and 7.

Referring to Figure 1, 1 represents the 75 overlapping and 2 the underlapping portion of a roofing member, a plurality of which, when constructed according to the present invention, are to be assembled upon a roof somewhat upon the principle of shingling. 80 In order that the roofing members may overlap to a minimum extent and still effect weatherproof joints between the several members, they are provided with ribs, ridges, flanges, or the like, hereinafter referred to 85 as "ribs", projecting from the plane of the member, and of which those ribs 3 which project from the overlapping portion of the member extend downwardly, while those which are upon the underlapping portion of 90 the member are presented upwardly, so that the downwardly projecting ribs on one mem- 95 ber may interlock with the upwardly projecting ribs on an adjacent member, and, as stated, the joint between two such members will be weatherproofed, and in addition said members will be prevented from drawing apart.

As will be seen in Figure 1a, when a plu- 100 rality of the members shown in Figure 1 are

assembled, the underlapping portion with its upwardly presented ribs affords an effective trough beneath the space that intervenes between the overlapped portions of two members in the next higher row.

In the particular form of member shown in Figures 1 and 1a, the overlapping portion is of relatively greater transverse relation than the underlapping portion, while 10 the dimensions of these two portions of the member in the direction of the watershed are substantially identical so that the two ends of each overlapping portion of one row may dip into the spaced troughs of the underlapped portions of the next lower row. By 15 this method of interengagement, the interlock is developed both longitudinally and transversely of the roofing member.

Roofing members of the form shown in 20 Figures 1 and 1a may be made from the blank 5 (Figure 2), and these blanks may be cut from a single strip without waste, as suggested in Figure 3.

As suggested in Figures 4 and 5, one longitudinal half of the strip shown in Figure 3 can be left uncut, so that some of the blanks 25 5 will be left attached to a continuous strip 2', and the roofing member will develop as shown in Figure 4 with a series of tabs 1, 2, 30 having the ribs 3, 4, but omitting the top-most rib that is employed in Figure 1, and instead, using the metal at that point to connect the tabs to the strip 2'.

In Figures 6 and 7, the overlapping portion 35 1 is provided with a depending rib 3 only at its lower transverse edge, while the underlapping portion 2' is a continuous strip from which the portions 1 project in the form of spaced tabs; and this continuous-strip 40 underlapping portion 2' is provided with transverse upwardly presented ribs 4 only to the extent of the spaces between the tabs.

A plurality of forms such as shown in Figures 6 and 7 will assemble as indicated in 45 Figure 8.

I claim:

1. Sheet roofing material comprising units adapted to be laid in rows with the units of an upper row overlapping those of a lower 50 row; said units having interlocking ribs on overlapping portions thereof; those ribs on an overlapping portion of the unit being presented downwardly, and those on an underlapping portion thereof being presented upwardly; the units of a row being united with a connecting strip which determines their spacing and their presentation upon the roof, and being connected with their strips through means of offsets which provide shoulders 55 through which to effect interlock with the units of a lapping row.

2. Sheet roofing material comprising units adapted to be laid in rows with the units of an upper row overlapping those of a lower 60 row; said units having interlocking ribs on

overlapping portions thereof; those ribs on an overlapping portion of the unit being presented downwardly, and those on an underlapping portion thereof being presented upwardly; said units comprising relatively wide and narrow portions and having connecting strips with which they are united through their narrow portions, and their narrow portions being complementary to their wide portions in a continuous area so that the units 70 may be cut from a continuous strip without waste. 75

3. Roofing members, each comprising a plurality of units constructed each with a wide portion and a narrow portion projecting therefrom and leaving offsets laterally beyond the narrow portions, interlocking flanges formed on the margins of the narrow portions and upon adjacent margins of the offsets and projecting in one direction from the plane of the unit, interlocking flanges formed on the remaining margins of the wide portions projecting in the opposite direction from the plane of the unit, and base members connecting a plurality of units together, 80 by means of their narrow portions, and spacing the units apart in a row with the distance between their narrow portions corresponding substantially to the width of the wide portions; said members being adapted 85 to be laid in superposed rows with the wide portions of units in one row closing the spaces between the narrow portions of the units in an adjacent row and interlocking with the margins of units of said adjacent row which 90 define said spaces. 95

4. Shaped roofing units cut from sheet material, and adapted to be laid in rows with portions of the units in one row overlapping portions of units in an antecedent row, said units having interlocking ribs on lapping portions thereof, and the individual units having outlines defining their shape which render them different at their two ends; the design at one end being complementary to 100 the design of the opposite end, so that a series of units alternately in reversed positions will correspond substantially to the complete area of the sheet material from which the units are cut. 110

5. A flexible shingle comprising a strip of material having spaced T shaped cut-outs formed in one edge of the strip, said edge having a marginal flange bent substantially at right angles therefrom, said shingle having flanges bent therefrom along the margin 115 of said cut-outs. 120

6. Roofing units, each constructed with a relatively wide portion and a relatively narrow portion projecting from said wide portion and leaving the wide portion offset laterally from the narrow portion; said units being adapted for application to a roof in rows and with the wide portions of the units of one row lapped with the narrow portions 125 130

of the units of an adjacent row, and also upon margins of the offsets of the wide portions, a wide portion being proportioned to bridge the space between two adjacent narrow portions with which it laps; the lapping of the units being provided with flanges through which they interlock.

5 Signed at Chicago, Illinois, this 14th day of July, 1920.

ALBERT C. FISCHER.
